(57) **CLAIM**

The ornamental design for a connector, as shown and described.

DESCRIPTION

FIG. 1 is a front elevational view of a connector showing my new design, in which the lever is shown in a first position; FIG. 2 is a rear elevational view thereof; FIG. 3 is a right side elevational view thereof; FIG. 4 is a left side elevational view thereof; FIG. 5 is a top plan view thereof; FIG. 6 is a bottom plan view thereof; FIG. 7 is a perspective view showing a front, top and right side thereof; FIG. 8 is a perspective view showing a rear, bottom and left side thereof; FIG. 9 is a perspective view showing a front, right and bottom side thereof; FIG. 10 is a perspective view showing a rear, left and top side thereof; FIG. 11 is a perspective view thereof, in which the lever is shown in a second position; and, FIG. 12 is a perspective view thereof, in which the lever is shown in a third position. The broken line showing of the connector is for the purpose of illustrating portions of the article and forms no part of the claimed design.

1 Claim, 12 Drawing Sheets
